WATER GAUGE

Filed Oct. 29, 1928

INVENTOR

THOMAS N. THOMSON

BY

ATTORNEY

UNITED STATES PATENT OFFICE

THOMAS N. THOMSON, OF HUNTINGTON, NEW YORK

WATER GAUGE

Application filed October 29, 1928. Serial No. 315,804.

The present invention relates to improvements in water gauges, one object of the invention being the provision of a novel form of gauge in which a colored liquid is adapted to be trapped so that the water level within the boiler may be readily observable through the gauge or sight glass of the present device.

Another object of this invention is the provision of a novel form of sight-glass supporting member in which is mounted a trap by means of which the indicating liquid, preferably a colored liquid such as an oil, is held trapped within the member and the sight-glass so that the level within the boiler will be readily observable through the sight-glass, and so that the colored liquid will not drain into the boiler when the latter is emptied, or when the boiler water line has inadvertently been permitted to rise above the gauge glass level.

Another object of this invention is the provision of a device of this character which is readily interchangeable with the present type of water gauge on boilers and which is simple, inexpensive and durable in construction and thoroughly efficient and practical in use.

With the foregoing and other objects in view, which will appear as the description proceeds, the invention resides in the combination and arrangements of parts and in the general construction hereinafter described and claimed, it being understood that changes in the precise embodiment of the invention herein disclosed can be made within the scope of what is claimed without departing from the spirit of the invention.

In the drawing:—

Figure 1 is a sectional view through part of the boiler, tank or the like, with the present device attached thereto, the lower supporting member of the present device being shown in vertical section;

Figure 2 is a section taken on line 2—2 of Figure 1;

Figure 3 is a section taken on line 3—3 of Figure 1;

Figure 4 is a sectional view through a modified form of trap chamber with an ordi-

nary type of gauge attached thereto and forming a modification of the present invention.

Referring to the drawing, the numeral 5 designates the boiler which is provided with two superposed aligned ports 6 and 7 to which are properly attached two respective supporting members 8 and 8' of the present device. As the member 8' is identical in construction with the member 8, a description of one will suffice for both. In the lower or extreme end of the member 8 is a threaded opening 9 which receives a draining pet-cock 10 or a sealing plug 10', as may be desired, a threaded nipple 11 being engageable with either one of the openings 6 or 7 to attach the same to the boiler. A valve seat 12 is provided, and aligned therewith is an interiorly threaded portion 13 sealed by a stuffing gland 14, while a threaded portion 15 of a valve 16 is mounted in the internally threaded portion 13 so that a stem 16' of the valve may be operated through a handle 17 to isolate the member 8 or 8' from the boiler.

An apron 18 is formed integral within the member 8 and forms a trap so that the colored liquid contained within the member 8 will be prevented from entering the boiler through the lower nipple 6, while formed in communication with this chamber is channel 19 opening through an exteriorly threaded portion 20 of the supporting member. The portion 20 is provided with an internal shoulder 21 for the reception thereupon of one end of a sight-glass 22, a packing ring 23 and a nut 24 being provided, as is usual, to properly support the glass in a liquid-tight manner.

In practice, the lower chamber 8 is filled with the indicating liquid L up to the base of the sight-glass 22, the same being accomplished in any desired manner but preferably by removal of the plug 10', the valves 16 being closed so that no water from the boiler can enter the chambers 8—8'. The valves 16 are now opened to assume the position as shown in Figure 1 and the water within the boiler will then cause the indicating liquid L to move upwardly in the sight-glass to assume the proper indicating level.

Where a colored oil is employed, the same being of less specific gravity than the water, the level of the indicating liquid will be slightly above the level of the water in the boiler, as clearly indicated in the drawing. When the boiler water line is down near the base of the sight-glass, the oil level is practically the same as the boiler water level. The differences between the exact water line indications are greater as the water line ascends, which is desirable in steam boilers.

In the construction shown in Figure 4, a member 8^a is provided with a trap or apron 25 which divides the member into two chambers and attached thereto is a lower coupling 26 of a usual water gauge now in common use, a valve 27 being of the usual construction and the sight-glass 22' being mounted in the usual manner.

The boiler 5 is indicated as having the member 8^a interposed between it and the usual gauge mechanism. This particular construction operates in a similar manner to the construction before described, but is not as neat in appearance nor as compact as the construction illustrated in Figure 1, it being necessary to add to the upper end of the gauge glass a similar member, such as 8^a, or a coupling of the same horizontal length, this, therefore, projecting the glass 22' farther away from the boiler than where the members 8 and 8' are employed.

The member 8' is disposed in a reverse direction to the member 8 so that its trap 18 (dotted lines) will act as an air trap to prevent the indicating liquid from entering the boiler through the nipple 7, should the boiler water line rise to or above said nipple, but will permit the natural movement of the indicating liquid up and down within the sight-glass.

By the use of an oil or, in fact, any colored liquid that may accomplish the same result and which is placed in the present device as above described, the usual dirt from the boiler which tends to soil the sight-glass so as to prevent the easy reading of the water level is prevented from accumulating, and due to the fact that the indicating liquid is colored, the same is readily discernible without manipulation of the pet-cock 10, as is usual with the present type of water gauge, to allow a certain amount of water to run out so that when the pet-cock is closed the water level can be more readily discerned.

I claim:—

1. A boiler water gauge including two superposed supporting hollow members, a colored liquid in the lower member, a sight glass supported between and in communication with the two members and into which the colored liquid rises for observation, a trap in the lower supporting member in line with the sight glass adapted to retain the colored liquid in the lower member and means on the

lower member operable to drain the gauge.

2. A boiler water gauge including two superposed supporting hollow members, a colored liquid in the lower member, a sight glass supported between and in communication with the two members and into which the colored liquid rises for observation, a trap in each of said supporting members for limiting the extreme rise and fall of the colored liquid, said traps and glass being arranged in substantially a single line, and means on the lower member operable to drain the gauge.

3. A boiler water gauge including two superposed supporting hollow members, a colored liquid in the lower member, a sight glass supported between and in communication with the two members and into which the colored liquid rises for observation, a trap in the lower supporting member to retain the colored liquid in the lower member, a valve in each supporting member operable to cut off communication of a boiler therewith and valve means on the lower member operable to drain the gauge.

4. A boiler water gauge comprising an upper supporting fitting and a lower supporting fitting for a sight member of a water gauge, each of said fittings comprising an elongated body providing a chamber, an apron in each of said chambers and forming a trap therein, the apron in the upper chamber extending upwardly and terminating short of the upper wall of said chamber and the apron in the lower chamber extending downwardly, said aprons being spaced from the opposite side walls of the chambers in which they are respectively mounted, said upper fitting having an opening in its lower end and said lower fitting having an opening in its upper end for connection, respectively, to the upper and lower ends of a sight member and each of said fittings having an opening in one of its side walls adjacent the end thereof opposite to the free end of the apron therein for communicating with a boiler.

5. A supporting fitting for a sight member according to claim 4 having a valve mounted on said body and operable to open or close the second mentioned opening.

6. A boiler water gauge comprising similar upper and lower supporting bodies adapted for communication with a boiler, a sight member communicating with the bodies, said bodies each having an apron providing a trap therein, the apron of the upper body extending upwardly and the apron of the lower body extending downwardly, an indicating liquid for travel in the gauge in advance of the water trap for observation in the sight member.

7. A boiler water gauge comprising similar supporting bodies adapted for communication with a boiler, a sight member communicating with the bodies, said bodies each having an apron providing a trap therein, said

6 aprons extending in opposite directions, an
10 indicating liquid for travel in the gauge in
advance of the lowermost trap for observation
in the sight member, each body having
an opening in one end thereof, the opening of
one of said bodies constituting a filling opening,
15 a closure for the latter opening, and
drain means for the opening in the other body.

8. A supporting body of the class described
10 having a body member, connections thereon
at an angle to each other having first and
second openings therethrough for connection
with a boiler and sight member, respectively,
15 an apron in the body member forming a
trap, said apron being opposite the first opening,
a valve mounting portion on the body extending
from the apron to the wall opposite
the second opening of a size to enable liquid
20 to pass around the same to the other opening,
and a valve in said mounting portion operable
to cover and uncover the first opening.

9. In combination with a boiler, a water
gauge fitting having a trap and an opening
25 between the trap and boiler, a valve within
the trap to close said opening, there being an
other opening between the trap and sight
glass, said trap having a substantially vertical
30 apron forming a tortuous passage from
one opening to the other, and a tubular portion
mounting said valve with its axis in line
with said opening and extending from the
apron to a wall of the fitting substantially as
shown and described.

10. The combination of two boiler water
35 gauge supporting fittings, a sight glass located
between said fittings, and a colored liquid
in the sight glass, each fitting having
two openings one for communication with a
boiler and the other with the sight glass, each
40 fitting having a trap apron between the two
openings thereof, said aprons having their
free ends extending away from each other,
substantially as shown and described.

11. A water gauge for boilers, comprising
45 a hollow body for supporting the upper end
of a water gauge glass and a second hollow
body for supporting the lower end of such
glass, an apron in the first named body ex-
50 tends upwardly and terminating short of
the upper wall of said body, an apron in the
second named body extending downwardly
and terminating short of the lower wall of
55 said body, each of said bodies having on one
side of the apron therein an opening for con-
nection to a boiler and on the opposite side
of such apron an opening for connection to
a water glass, a water glass supported be-
60 tween and in communication with the last
named openings of said bodies, and a colored
liquid in said water glass.

In testimony whereof I have hereunto set
my hand.

THOMAS N. THOMSON.
